HONE

Howard W. Dunbar, Worcester, and Herbert S. Indge, Westboro, Mass., assignors to Norton Company, Worcester, Mass., a corporation of Massachusetts

Application April 28, 1938, Serial No. 204,750

3 Claims. (Cl. 51—184.3)

The invention relates to hones and with regard to its more specific features to the expansion type of hone.

This application is a continuation in part of our copending application Serial No. 191,478 filed February 19, 1938.

One object of the invention is to provide a hone which will expand during the honing operation as the metal is honed. Another object of the invention is to provide a thermally controlled hone. Another object of the invention is to provide a hone the entire control of which is thermal and which may be controlled by controlling the temperature of the honing liquid.

Another object of the invention is to provide a novel method of honing whereby delicate control of the diameter of the hone may be effected. Another object of the invention is to provide a honing tool of simple construction. Another object of the invention is to provide a quickly adjustable honing tool having also an automatic adjustment over a micrometer range. Another object of the invention is to provide a honing tool which can be adjusted while the hone is in operation to fine precision limits. Other objects will be in part obvious or in part pointed out hereinafter.

The invention accordingly consists in the features of construction, combinations of elements and arrangements of parts, as will be exemplified in the structure to be hereinafter described and the scope of the application of which will be indicated in the following claims.

In the accompanying drawing illustrating one of many possible embodiments of the mechanical features of this invention:

Figure 1 is an axial sectional view of the honing tool;

Figure 2 is a cross sectional view taken on the line 2—2 of Figure 1; and

Figure 3 is a diagrammatic view of honing apparatus including the honing tool.

Referring to Figure 3, practically any form of drill press, not shown, may be used having a chuck to hold the hone and to rotate it and to allow it to be raised and lowered at the will of the operator. In Figure 3 a chuck 8 is shown containing a hone 9 held by its arbor 10 in the chuck.

Referring now to Figure 1, below the arbor 10 is a universal joint 11. The bottom element 12 of the universal joint is connected by a cross pin 13 to a sleeve 14. Sleeve 14 has a long spline 15 in which is located a pin 16 extending through an outer sleeve 17. The sleeve 17 has a top flange

18 under which is a bottom flange 19 of a collar 20. An inside collar 21 fits in the collar 20 and is fastened to it by screws 22. The collar 21 is internally threaded and constitutes a nut and is in threaded engagement with a threaded portion 23 of the sleeve 14.

By the construction so far described, the sleeves 14 and 17 are supported by the universal joint 11 and the arbor 10. They are angularly fixed relative to each other by means of the pin 16. Nevertheless they can move axially relative to each other and may be moved by turning the collar 20.

The sleeve 17 has an integral extension 27 on the bottom thereof of somewhat larger diameter than the portion 17. This extension 27 of the sleeve 17 has a plurality of upper apertures 28 and a plurality of lower apertures 29. In the extension 27 are located a pair of hollow cones 30 and 31 facing in opposite directions, as shown. Pivoted at 32 to the sleeve 14 in notches 33 thereof are rock levers 34. The bottom of the extension 27 is threaded at the inside as shown at 35 and a ring 36 is screwed into it, this ring having slots 37 therein in which are pivotally mounted by means of pins 38, rock levers 39 just like the rock levers 34.

The inner ends of the rock levers 34 rest on a shoulder 40 of a pin 41. The inner ends of the rock levers 39 rest on a shoulder 42 of a pin 43. The pins 41 and 43 are located in the cams 30 and 31.

The cones 30 and 31 each have deep countersinks 44. In these countersinks are springs 45. Between the pins 41 and 43 is a thermostatic member indicated by the numeral 50. This consists of curved disks 51 joined together in pairs, as by soldering or the like. Each pair of disks 51 contain a suitable liquid and each pair expands on being heated.

We provide honing sticks 55 which may be made of any suitable abrasive bonded with the desired bond. For instance, these may be made of crystalline alumina, silicon carbide or diamond abrasive bonded with vitrified ceramic bond, or metal bond, or resinoid bond, or in some cases rubber bond. Referring to Figure 2, each stick 55 is cemented to a channel support 56. Referring to Figure 1, the channel supports 56 fit in holders 57 which are fork-shaped and have inclined surfaces 58 cooperating with the cones 50 and 51. Clip springs 60 removably hold the channel supports 56 to the holders 57. Garter springs 61 engaging portions 62 of the channel supports 56 hold the parts together. There may be any number of the units including the abra-

sive stones 55 from three up to an indefinite number, for example seven.

Referring now to Figure 3, the honing tool 9 is shown honing the cylindrical bore of a work piece 70 which is supported on a table 71. Above the work piece 70 and constituting both a guide for entry of the honing tool 9 and a clamp for the work piece 70 is a sleeve 72 held against the work piece 70 by any suitable means, not shown. In the side of the sleeve 72 is a bore 73 which is connected to a pipe 74 merging into two pipes 75 and 76 in which are valves 77 and 78. The pipe 75 connects to a spiral pipe 79 in a cylinder 80. The pipe 79 is connected to a pipe 81. Both of pipes 76 and 81 are connected to a pipe 82 which is connected to a pump 83 pumping liquid, such as kerosene, out of a sump 85.

The pump 83 pumps kerosene ultimately through the pipe 74 into the sleeve 72 whence it flows into the bore in the work piece 70, flooding the honing tool 9. Thence the kerosene drips back into the sump 85. We provide further a steam pipe 90 and a return pipe 91 to fill the cylinder 80 with live steam. This heats the kerosene in the spiral pipe 79. The operator may, by adjusting the valves 77 and 78, control the temperature of the kerosene in the sleeve 72 and work piece 70.

The thermostat 50 is sensitive to heat and, when the temperature rises, it expands and thereby through the mechanism described expands the honing sticks 55. The operator can thus control the honing operation, causing more pressure to be exerted against the honing stick at any time. Such control is free from mechanical connections through the sleeve 14 and arbor 10 and thus mechanical construction of the upper part of the hone is simplified. Major adjustments can be made to adapt the hone to different sizes of bores by turning the collar 20.

In the use of the invention, the hone may be contracted mechanically by turning the collar 20 until it will readily pass into the work piece, and then expanded until the abrasive elements 55 evenly press against the work piece. The hot and cold fluid is then turned on until a thermometer 93 in the pipe 74 reads approximately the same as room temperature. The hone is now rotated and reciprocated by the controls provided on the machine tool, not shown. There is thus produced a light abrading action. The hot valve 78 is now opened a little bit wider un-

til the temperature is seen to rise on the thermometer 93. This will expand the liquid between the pairs of thermostat disks 51 which will expand the abrasive elements 55 of the hone.

One feature of the invention resides in the fact that once the honing sticks have expanded, they cannot be contracted merely by outside pressure. This is because the levers 34 and 39 have a mechanical advantage in favor of the bellows 50 and against the stones 55.

The bellows 50, when heated, exert considerable pressure and by reason of the mechanical advantage mentioned and the cone action this pressure is considerably increased at the abrasive stones 55.

It will thus be seen that there has been provided by this invention apparatus and a method in which the various objects hereinabove set forth together with many thoroughly practical advantages are successfully achieved. As various possible embodiments might be made of the mechanical features of the above invention and as the art herein described might be varied in various parts, all without departing from the scope of the invention, it is to be understood that all matter hereinbefore set forth or shown in the accompanying drawing is to be interpreted as illustrative and not in a limiting sense.

We claim:

1. In apparatus of the class described, a sleeve, a shank, connections between the sleeve and the shank, a pair of cones in the sleeve, projections engaged by the cones, abrasive elements on the outside of the sleeve connected to the projections, a bellows between the cones, and adjustment means to adjust the position of the cones for a given elongation of the bellows.

2. In a hone, a plurality of abrasive sticks, a supporting structure supporting said sticks in parallel relation around the periphery of said supporting structure, a thermostatic device inside of said supporting structure, and mechanical connections between said thermostatic device and said abrasive sticks.

3. In apparatus as claimed in claim 2, the combination with the parts and features therein specified, of means to prevent retrograde action of said device by pressure from outside.

HOWARD W. DUNBAR.
HERBERT S. INDGE.
